Fig. 2.

UNITED STATES PATENT OFFICE

ANDREW GARBUZZ, OF BOSTON, MASSACHUSETTS.

DESIGN FOR A COOKING STOVE OR RANGE.

SPECIFICATION forming part of Design No. 16,189, dated August 4, 1885.

Application filed June 29, 1885. Term of patent 7 years.

To all whom it may concern:

Be it known that I, ANDREW GARBUZZ, a subject of the Queen of Great Britain, residing at Boston, in the county of Suffolk and State of Massachusetts, have invented certain new and useful Improvements in Designs for Cooking Ranges or Stoves, of which the following is a specification, reference being had therein to the accompanying drawings.

10 Figure 1 is a three-quarter view of my newly-designed cooking range or stove. Fig. 2 is a view of the tank-panel H. Fig. 3 is a view of the rear panel I.

The leading features of my design consist 15 of a cooking range or stove with its large oven-door A, fire-door B, tank-panel D, grate-door C, low closet-doors E and G, side panels F and H, and side panel I, ornamented as follows:

20 The oven-door A is ornamented by a molding consisting of a large round and hollow, broken by two fillets, and five beads or reeds, the whole inclosing a central panel in imitation of hammered silver, with a conventional 25 rosette in the lower left-hand corner, foliated hinges, and conventionalized flower knob-seat.

The fire-door B is ornamented by same design for its hinges, and has a molding of same 30 design, with four beads or reeds surrounding a central panel of conventionalized honeysuckles springing from a central bulb.

The grate-door C is ornamented by a molding of the same design as door A, only with 35 three beads or reeds surrounding a double panel, the upper one of which is ornamented

by convex conventionalized honeysuckle-scrolls surrounding mica lights.

The low closet-doors E and G are ornamented with moldings consisting of a round and hollow, broken by two fillets, and four beads or reeds, with smaller central imitation ham-mered-silver panels, and foliated hinges similar to that of oven-door A.

The side panels F and H are ornamented 45 by same molding inclosing a panel of conventionalized honeysuckles springing from a central bulb.

The side panel I is ornamented by a central 50 medallion in the form of conventionalized honeysuckles springing from a central bulb, and surrounded by a molding consisting of a large round and hollow, broken by two fillets, and six beads or reeds.

The water-tank is ornamented by a panel, 55 D, consisting of a molding, two fillets, and four reeds, surrounding a central panel consisting of conventionalized honeysuckles springing from a bulb in lower corner.

I claim—

The design for a stove or range of the shape shown, having its oven-door, fire-door, tank-panels, grate-door, low closet-doors, knob-seat, and side panels ornamented by figures, flowers, rosettes, and molding, as shown and 65 described.

In testimony whereof I affix my signature in presence of two witnesses.

ANDREW GARBUZZ.

Witnesses:

ALBERT N. HOXIE,
P. J. DOHERTY.
